UNITED STATES PATENT OFFICE.

THOMAS H. McGOWAN, SR., OF STONINGTON, CONNECTICUT, ASSIGNOR TO DRAPER CORPORATION, OF HOPEDALE, MASSACHUSETTS, A CORPORATION OF MAINE.

SHUTTLE FOR AUTOMATIC FILLING-REPLENISHING LOOMS.

Application filed July 28, 1922. Serial No. 578,168.

To all whom it may concern:

Be it known that I, THOMAS H. McGOWAN, Sr., a citizen of the United States, and resident of Stonington, county of New London, 5 State of Connecticut, have invented an Improvement in Shuttles for Automatic Filling-Replenishing Looms, of which the following description, in connection with the accompanying drawing, is a specification, 10 like characters on the drawing representing like parts.

This invention relates to improvements in shuttles for automatic filling replenishing looms and the object thereof is to provide a 15 thread cutter carried by the shuttle which will sever the filling running from the web of cloth to the discharged filling carrier during the first pick of the shuttle after transfer.

In usual automatic loom constructions the 20 filling extending from the web of cloth to the filling carrier which is discharged upon transfer is clamped and severed by the shuttle feeler thread cutter. It has been found that in some instances, particularly where 25 heavy filling is used such as that of tire duck fabric, the shuttle feeler thread cutter fails to sever the filling and since the filling is very coarse, with a high number of ply, it will not break during the unwinding of 30 the filling carrier so that the filling end extending to the discharged shuttle is carried into the web of cloth during the next pick after transfer and possibly during two or three picks, thus producing an imperfection 35 in the cloth which must be removed by hand. Where the filling is thus removed it is difficult to remedy the imperfection. By the present invention the shuttle is provided with a cutter which acts during the first pick 40 of the shuttle after transfer to sever the running bight of the filling which extends from the web of the cloth to the discharged filling carrier when the bight is in proximity to the selvage of the cloth so that a very 45 short end is left which, if drawn into the cloth, can be readily removed by hand without causing an imperfection in the weave.

A further object of the invention is to provide a thread cutter of this type which 50 can be readily applied to usual types of threaders.

A further object of the invention is to provide a cutter of the character which can be secured within the threader by the same

means which secures the threader to the 55 shuttle.

A further object of the invention is to provide a cutter of the character described with means for supporting the filling in substantially the horizontal plane of the thread 60 eye of the shuttle.

Other objects and features of the invention will more fully appear in the following description and the accompanying drawings and will be pointed out in the claims. 65

A preferred embodiment of the invention is disclosed in the accompanying drawing as applied to a shuttle having a sheet metal threader such as the general type illustrated in Patent No. 933,497 granted September 7, 1909 to E. S. Stimpson, but it will be understood that the invention is adapted to be embodied in any suitable threader to which it may be applicable.

In the drawings:

Fig. 1 is a plan view of the end portion of the shuttle showing the threader and cutter embodying the invention;

Fig. 2 is a vertical median longitudinal section of the same;

Fig. 3 is a vertical longitudinal sectional view similar to Fig. 2 showing the running bight of the filling in the position in which the bight is severed during the first pick of the shuttle after transfer.

The shuttle illustrated in the accompanying drawing is of the usual type having a body 1 provided with a chamber 2 to receive the filling carrier 3 and provided with a channel in its end portion in which the 90 threader 4 is mounted.

The threader 4, which is of the general type illustrated in the Stimpson patent above referred to, is formed of sheet metal to fit in the channel and is provided at its front end with an overhanging shield 5 and a bight 6 which serves to guide the filling through the usual threading slot into the eye 7 of the shuttle. The rear end of the threader is provided with a guard 8 which overlies the 100 path of the filling and serves to prevent it from being thrown from the threader.

The rear end of the threader is provided with an extension 9 which is bent upwardly and this extension, together with the lower 105 wall of the threader is provided with a slot 10 which extends beneath the cutter which will hereinafter be described. The body of

the shuttle is provided with a recess 11 which lies beneath the threader and the slot 10 to enable the running bight of the filling to be carried abruptly around the edge of the cutter blade.

The preferred form of cutter illustrated herein comprises a rigid block 12 of a width to fit the channel in the threader and is provided with an aperture to receive the bolt 13 which secures the threader in the shuttle. Thus the cutter blade and threader are secured in the shuttle by the same means. The upper portion of the body of the cutter desirably is curved and the crest 14 of the curve lies substantially in the plane of the axis of the thread eye of the shuttle so that this curved surface serves to support and guide the filling to the thread eye. The cutter is provided with an edge 15 which is located below the horizontal plane of the axis of the thread eye and extends toward the chamber in the shuttle which receives the filling carrier. The blade preferably abuts against the upwardly turned members of the threader extension 9 so that the slot 10 in the latter, which desirably converges downwardly, serves to direct the filling against the central portion of the edge of the cutting blade.

In the operation of the device, where the shuttle thread cutter fails to sever the filling running from the web of cloth to the filling carrier which is discharged during transfer, the first pick of the shuttle after transfer forms a running bend or bight 16 in the filling around the edge of the cutting blade as the shuttle moves across the lay. During the beginning of this flight of the shuttle the filling runs freely across the cutting edge as the shuttle approaches the selvage of the web of cloth. When, however, the shuttle passes the selvage the filling is drawn forcibly against the blade and severed. This action of the shuttle is illustrated in Fig. 3 in which the filling 17, which extends from the selvage 18 of the cloth to the discharged filling carrier, is illustrated as being bent sharply around the cutting blade 16. At this time the weight of the discharged filling carrier imposes a tension upon the filling 17 which acts in opposition to the tension upon the portion 19 of the filling extending from the selvage 18 to the blade so that further movement of the shuttle (to the left) causes the filling to be severed in proximity to the selvage of the cloth. By reason of this operation the severed filling end is only two or three inches long and if whipped into the cloth can be readily removed without causing an imperfection in the web of the cloth.

While it is primarily intended to employ the present invention in connection with the usual shuttle feeler thread cutter it will be obvious that the same will operate in the

manner above described even in the absence of a shuttle feeler thread cutter.

It will be understood that the embodiment of the invention disclosed herein is illustrative and not restrictive and that various changes in form, construction and arrangement of parts may be made within the spirit and scope of the invention, and further that the invention may be embodied in various other types of threaders than that particularly illustrated herein.

Having thus described my invention, what I claim as new, and desire to secure by Letters Patent, is:

1. A shuttle for automatic filling replenishing looms having means carried thereby acting during the first pick of the shuttle after transfer to sever the filling extending from the web of cloth to the discharged filling carrier.

2. A shuttle for automatic filling replenishing looms having a cutter carried thereby acting by the movement of the shuttle during the first pick after transfer to sever the filling extending from the web of cloth to the discharged filling carrier in proximity to the selvage of the cloth.

3. A shuttle for automatic filling replenishing looms having a filling carrier chamber, a rigid cutting blade presenting an edge toward the filling carrier chamber acting during the first pick after transfer to sever the running bight in the filling which extends from the web of the cloth to the discharged filling carrier when said running bight is in proximity to the selvage of the cloth.

4. A shuttle for automatic filling replenishing looms having a filling carrier chamber, a threader having a slot in its bottom communicating with said chamber and a recess in the shuttle body underlying said slot, and a cutting blade presenting an edge extending toward said chamber overlying the slot in said threader acting during the first pick after the transfer to sever the filling in proximity to the selvage of the cloth.

5. A shuttle for automatic filling replenishing looms having a filling carrier chamber, a threader having a slot in its bottom communicating with said chamber and a recess in the shuttle body underlying said slot, a cutting blade presenting an edge extending toward said chamber, overlying the slot in said threader, acting during the first pick after transfer to sever the filling in proximity to the selvage of the cloth and filling guiding members extending upwardly from the bottom of the threader acting to direct the bight formed during the first pick toward the central portion of said cutter.

6. A shuttle for automatic filling replenishing looms having a filling carrier chamber, a threader having a slot in its bottom communicating with said chamber and a re-

- cess in the shuttle body underlying said slot, a cutting blade presenting an edge extending toward said chamber overlying the slot in said threader acting during the first pick 5 after transfer to sever the filling in proximity to the selvage of the cloth and means acting to secure both the threader and the cutting blade in the shuttle.
7. A shuttle for automatic filling replenishing looms having a filling carrier chamber, a threader to receive and guide the filling from the filling carrier to the eye of the shuttle provided with a slot in its bottom, a recess underlying said threader communi- 10 cating with said slot, a cutting blade having 15 a filling supporting and guiding portion located substantially in the horizontal plane of the shuttle eye and having a cutting edge located below said plane extending toward the chamber of said shuttle acting during 20 the first pick after transfer to sever the running bight in the filling which extends from the web of cloth to the discharged filling carrier when said bight is in proximity to the selvage of the cloth. 25
- In testimony whereof, I have signed my name to this specification.

THOMAS H. McGOWAN, SR.
